UNITED STATES PATENT OFFICE.

THADDEUS F. TYLER, OF HAVERHILL, MASSACHUSETTS.

SUPPORTING DEVICE.

Application filed June 19, 1925. Serial No. 38,383.

To all whom it may concern:

Be it known that I, THADDEUS F. TYLER, a citizen of the United States, residing at Haverhill, in the county of Essex and State 5 of Massachusetts, have invented certain new and useful Improvements in Supporting Devices, of which the following is a specification.

This invention relates to a supporting device, designed primarily for supporting carriers for heel coverings, but it is to be understood that a supporting device, in accordance with this invention, can be employed for any purposes for which it is found applicable, and the invention has for its object to provide, in a manner as hereinafter set forth, a supporting device to expedite the application of coverings to wooden or other heels in the manufacture of foot wear.

In the manufacture of foot wear, more particularly to that type provided with solid heels of wood or other material, the heels are first formed and after which each heel is covered with flexible material, preferably 10 leather and in most instances corresponding to the material from which the upper is formed. The covering is attached to the heel through the medium of an adhesive substance in the form of a paste or glue, and after the covering has been applied to the heel the latter is mounted on a suitable 15 drying machine. The coverings which are to be applied to the heel are mounted on a carrier which consists of a sheet of paper, and prior to the mounting of the coverings 20 on the carrier they are provided with an adhesive substance so that when a covering is removed from the carrier it is in condition to be applied to the heel. The carrier is mounted on a wooden board and in some instances to prevent the carrier from slipping from the board, it is detachably secured therewith by a cementitious substance. 25 After the coverings, which are detachably secured to the carrier, have been removed therefrom and applied to the heel, the carrier with its supporting board is taken by the operator to a place of supply and from there the operator obtains a filled carrier 30 and its supporting board. As the carrier, which is formed of paper, is detachably secured to its supporting board, it has been found that when removing the carrier from the board, it becomes torn or damaged and which makes it unfit to be filled again with 35 coverings.

Considerable time is lost by the operator when a carrier is emptied and a filled one obtained in the manner as referred to, and as the support for the carrier, which is constructed of wood, is not provided with any means to hold the carrier, the latter often-times when removing a covering therefrom shifts off the board onto the floor and damages the coverings. Furthermore as the 40 board is constructed of wood its life is not very long.

A supporting device, in accordance with this invention, includes means for engagement with the carrier to prevent the same 45 from slipping therefrom, and furthermore the carrier supporting element of the device is not formed of wood but constructed of compressed fiber or metal, preferably fiber, whereby the life of said element is materially greater than when such element is constructed of wood. By providing the device with means to detachably secure a carrier therewith, a supply of carriers, sufficient for a day's use, can be positioned and held on 50 the supporting element, and by such arrangement it overcomes the loss of time in going to a place of supply and obtaining a filled carrier after one has been emptied. When positioning a number of carriers on 55 the supporting device, a damp cloth is interposed between the carriers to prevent the adhesive substance from becoming hard on 60 the coverings before these latter are applied to the heels.

The support or board for the carrier, as now used, does not include any means for shifting or positioning the board so that the operator can conveniently remove a covering, as the board is laid flat on the bench 65 and the first half of the coverings can be removed from the carrier in a satisfactory manner, but when the operator comes to the last half, the board is partly pulled off the bench and if it is pulled off too far it 70 falls onto the floor and damages the coverings. This objection is overcome by a supporting device, in accordance with this invention, as the device includes means whereby the carrier supporting element is carried 75 by a supporting means fixed to the bench and with the supporting means having provisions whereby the carrier supporting element can be adjusted at various angles to enable the heel covering to be in convenient 80 reach of the operator at all times.

Further objects of the invention are to

provide, in a manner as hereinafter set forth, a supporting device for the purpose referred to, which is simple in its construction and arrangement, strong, durable, compact, adjustable, thoroughly efficient and convenient in its use, readily assembled, providing for a material saving in cement and paper over the method now employed in applying coverings to heels, and inexpensive to set up.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a front elevation, broken away, of a supporting device, in accordance with this invention.

Figure 2 is a side elevation.

Figure 3 is a fragmentary view in elevation, looking towards the front end of the supporting device.

Figure 4 is a section on line 4—4, Figure 1.

Figure 5 is a section on line 5—5, Figure 1.

Figure 6 is a plan of the base of the device.

Referring to the drawings in detail, a supporting device for the purpose referred to, includes a carrier supporting element 1 and which consists of a rectangular member formed of fiberoid, compressed fiber or metal, preferably fiber, and which is provided near its upper and lower ends, at one side thereof, with a spring clamp, indicated at 2, 3. The function of the clamps 2, 3, is for the purpose of detachably connecting to the element 1, one or more carriers, such as a sheet of paper, provided with a series of heel coverings having a cementitious substance applied thereto for the purpose of securing the covering to a heel. The carrier is not shown as it forms no part of the invention. The element 1 is disposed at an inclination, that is it inclines upwardly from its front towards its rear end, see Figure 2, and such inclination is fixed. The element 1 is detachably connected to a supporting means therefor, and the latter can be shifted to position the element at various angles to enable the heels to be positioned in convenient reach of the operator. The element 1, when adjusted to various inclinations, is shifted on its transverse axis. The supporting means for the element 1 will be presently referred to.

The supporting device further includes a base 4 consisting of a flat bar formed at one side with a series of projections 5, 6 and 7 and each of which is apertured, as at 8, for the passage of a hold-fast device 9 to fixedly secure the base 4 to a bench 10, or an extension of a drying machine. One end of the base 4 is formed with a pair of vertically disposed spaced apertured ears 11, and the other end of the base 4 is also provided with a pair of vertically disposed spaced apertured ears 12. Secured to the base 4, at its transverse center, and at each side of its longitudinal center, is a vertically disposed eye-bolt and said bolts are indicated at 13, 14 and provide means for anchoring the lower ends of a pair of controlling springs to be presently referred to.

Extending through the apertured ears 11 and 12, as well as projecting outwardly from the outer ear of the pair of ears 11, is an adjusting shaft 15, carrying on that end which projects from the outer ear of the pair of ears 11 a handle or crank 16. The other end of the shaft 15 is provided with a securing nut 17, which abuts against the outer ear of the pair of ears 12. The handle 16, in connection with the nut 17, prevents lengthwise shifting of the shaft 15 with respect to the two pair of ears 11, 12. The shaft 15 extends between the eye-bolts 13, 14.

Fixedly secured to the shaft 15, between the pairs of ears 11, is a supporting arm 18 provided with an inwardly extending lug 19, and fixedly secured to the shaft 15, between the pairs of ears 12 is a supporting arm 20 provided with an inwardly extending lug 21. Pivotally connected to the upper end of the arm 18 by the pivot 22, is the lower end of a clamping arm 23 formed with an inwardly extending lug 24, which abuts against the lug 19 to arrest the inward shift of the arm 23, and pivotally connected to the upper end of the arm 20 by the pivot 25, is a clamping arm 26 provided with an inwardly extending lug 27, which abuts against the lug 21 to arrest the inward shift of the arm 26. The arm 23 is of T shape, and the head 28 thereof is provided with a lengthwise extending groove 29, which opens at the inner side of the head. The lower portion of the head 28, as indicated at 30, is of greater width than the upper portion, whereby said lower portion will project inwardly with respect to the upper portion. The arm 26 is of T shape and the head 31 thereof is provided with a lengthwise extending groove 32, which opens at the inner side of the head. The lower portion of the head 31, as indicated at 33, is of greater width than the upper portion and projects inwardly therefrom. By setting up the lower portion of the heads 28 and 31 of greater width than the upper portion,

the lower wall of each groove is of greater width than the upper wall.

The element 1 is adapted to be positioned within the grooves 29 and 32, see Figure 2, so that said element 1 will be supported. The arm 23 is of less height than the arm 26, whereby when the element 1 is mounted in the heads 28 and 31, it will be supported at an inclination and with the inclination 10 extending upwardly from the outer towards the inner end of the element 1. The arms 23 and 26 are maintained in clamping engagement with respect to the element 1, through the medium of a pair of controlling 15 springs 34, 35. The spring 34 has one end connected to an eye 36 carried by the arm 23, and its other end attached to the eye-bolt 14. The spring 35 has one end attached to an eye 37, carried by the arm 26 20 and its other end connected to the eye-bolt 13. The springs 34 are disposed at an inclination and incline upwardly from the eye-bolts 13, 14 to the eyes 36, 37. The springs 34 and 35 extend in opposite directions with respect to each other and normally tend to maintain the arms 23 and 26 25 in a vertical position and in clamping relation with respect to the element 1.

The arms 23 and 26 are shifted outwardly 30 on their pivots for the purpose of removing the element 1 from the heads thereof. The element 1 is adjusted at various angles by shifting the shaft 15. The grooves 29 and 32 are of a size to snugly fit the element 1, 35 and when the latter is mounted in the arms 23, 26, its side edges abut against the inner walls of the grooves. The springs 34 and 35 are of such character as to maintain the arms 23 and 26 in frictional engagement with 40 the element 1 to prevent the slipping thereof relative to said arms when the element 1 is adjusted on its transverse axis.

It is thought that the many advantages of a supporting device, in accordance with

this invention and for the purpose set forth, 45 can be readily understood, and although the preferred embodiment of the invention is as illustrated and described, yet it is to be understood that changes in the details of construction can be had which will fall 50 within the scope of the invention as claimed.

What I claim is:—

1. A supporting device for the purpose set forth comprising a heel covering carrier supporting element having means for detachably connecting the carrier therewith, and means for supporting said element at a permanent inclination and further for adjusting the element at an angle when supported at an inclination. 60

2. A supporting device for the purpose referred to comprising a heel covering carrier supporting element, and a support for said element, said support including means for permanently positioning said element at an 65 inclination and further for adjusting said element at an angle when supported at an inclination.

3. A supporting device for the purpose set forth comprising a heel covering carrier supporting element provided with means for detachably connecting the carrier therewith, and a support for said element, said support including means for detachably clamping said element at an inclination and for 70 adjusting said element at various angles when in said inclined position.

4. A supporting device for the purpose set forth comprising a heel covering carrier supporting element, a support therefor 80 including a stationary base, said support further including means for detachably clamping said element at an inclination and for adjusting said element at various angles when clamped at an inclination. 85

In testimony whereof, I affix my signature hereto.

THADDEUS F. TYLER.
